US00D756307S

(12) **United States Design Patent**
Ruddick

(10) **Patent No.:** **US D756,307 S**
(45) **Date of Patent:** **** May 17, 2016**

(54) **CABLE CONDUIT**

(71) Applicant: **D-Line (Europe) Limited**, Tyne and Wear (GB)

(72) Inventor: **Paul David Ruddick**, Tyne and Wear (GB)

(73) Assignee: **D-Line (Europe) Limited**, Tyne and Wear (GB)

(**) Term: **14 Years**

(21) Appl. No.: **29/484,019**

(22) Filed: **Mar. 5, 2014**

Related U.S. Application Data

(62) Division of application No. 29/398,404, filed on Jul. 29, 2011, now Pat. No. Des. 703,151.
